METHOD OF SIZING PHOTOGRAPHIC PAPER

Gerould T. Lane, Rochester, N. Y., assignor, by
mesne assignments, to Eastman Kodak Company,
Jersey City, N. J., a corporation of New Jersey

Application March 12, 1935, Serial No. 10,635

8 Claims. (Cl. 91—68)

This invention relates to paper making and particularly to a method of and apparatus for sizing paper. One object of my invention is to provide an improved method of sizing paper by which the size can be made to fully penetrate the paper web. Another object of my invention is to provide a method of sizing paper including driving out the air in a paper sheet, and permitting atmospheric pressure to cause the size to penetrate the sheet. Another object of my invention is to provide a method of sizing paper by steaming and excluding air from the steamed paper until after it passes through the sizing bath. Another object of my invention is to provide a simple machine for aspirating paper before sizing. Another object is to provide a machine in which paper is passed against a counter-current flow of gas before entering the size. Still another object is to provide an operable steam chest at the entrance to a sizing bath, and other objects will appear from the following specification, the novel features being particularly pointed out in the claims at the end thereof.

In the past, sizing has been one of the most difficult steps to accomplish properly in paper making. It is desirable to use a concentrated size so that a single treatment will size the paper with size of the desired strength, but if concentrated size is used, only the surface is treated and but little size penetrates to the interior of the sheet. Since the fibers are not cemented well together, the resulting sheet is not strong.

On the other hand, if thin or dilute size is used, the sheet may be wetted quite fully, but the dilution is such that the fibers, while wetted, are not properly cemented together because so little size gets into the sheet. Here too, the sheet is not nearly as strong as it might be.

Consequently, sizing has generally been a common promise in which paper strength has been definitely sacrificed. If proper strength size is made to penetrate throughout a sheet or web of paper, so that all the fibers are cemented together, a paper sheet can be made many times stronger than the present practice with fibers of the same length and character.

It is to overcome these sizing difficulties, which are well-known in the art, and are particularly well-known to makers of fine, high strength papers which must be used in various arts requiring treatments which dampen or wet the paper, such as for photography, lithography, art work, etc., that the present invention was made. I have been able to size with a concentrated solution (say 6 per cent) and to cause the size to

penetrate fully into the body of the sheet, and to actually over-size paper by the method and apparatus which will now be described.

Coming now to the drawings in which like reference characters denote like parts throughout: 5

Fig. 1 is a side elevation partially in section, showing an apparatus for sizing paper constructed in accordance with and embodying a preferred form of my invention.

Fig. 2 is an enlarged fragmentary sectional view of the apparatus shown in Fig. 1.

Fig. 3 is an enlarged cross-section of the steam chest used with a preferred form of my sizing apparatus.

Fig. 4 is a fragmentary detail of a second embodiment of my invention showing the means for adjusting the width of the paper entrance to the steam chest.

Fig. 5 is an enlarged sectional view taken on line 5—5 of Fig. 4. 20

In accordance with the drawings wherein a preferred form of my invention is shown, I may provide an apparatus for sizing paper, as shown in Fig. 1, wherein there is a tank 1 which is adapted to hold sizing solution 2 which may be brought up to a predetermined level 3. At one end of the tank 1, there is mounted a steam chest designated broadly as 4 in which there is an aspirator for treating the paper, this aspirator being operated by means of steam which may be passed to the steam chest 4 through the pipes 5 and 6, the amount of steam being controllable by means of the valves 7 and 8.

A bracket 9 on top of the steam chest supports a roller 10 over which a paper web P may be drawn directly from the drying rolls 11.

Beneath the steam chest a guide roller 12 is mounted, and the paper web P is drawn beneath this guide roller through the sizing solution around a second guide roller 13 mounted in the opposite end of the sizing tank 1. Above roller 13, there is mounted a pair of squeezing rollers 14 and 15. These rollers may be of granite and rubber, as is customary, and are for squeezing off the excess sizing remaining on the paper web P as it is drawn from the sizing solution. The paper web passes continuously over a second series of drying rollers 16. This sizing apparatus is arranged to permit the paper web P to move continuously at a relatively high speed. In fact I have found that the sizing operation is no longer a limiting factor in the speed of operation of the machine and that I can completely size paper as fast as the web can be formed on the making wire. 55

As indicated in Figures 2 and 3, the steam chest 4 preferably consists of two sections 17 and 18 which are hinged together at 19, so that one section can swing relative to the other. I 5 provide bolts or screws 20 at the end opposite to the hinge 19 these fasteners, passing through the cooperating flanges 21 and 22, so that the two sections can be held firmly together after the paper has been threaded through the steam 10 chest in initially threading up the machine.

I prefer to provide the steam chest 4 with a covering of suitable insulation material, such as asbestos cement, or the like, as indicated at Fig. 3 at 64, since this is useful in keeping the 15 interior of the steam chest at a constant temperature and preventing too great a loss of heat. I also prefer to provide drains 32' and 33' in each bottom section to carry off any water which may form if steam condenses.

20 Referring to Fig. 3, the steam chest 4 is provided with a pair of walls 24 and 25 which are fastened to flanges 26 and 27 at the upper walls 28 and 29 of the steam chest, the lower edges 30 and 31 of these plates being spaced some 25 distance above the bottom walls 32 and 33. These converging walls form an aspirator when steam passes upwardly between these walls about both sides of the paper web P as it is moving downwardly between the walls. The counter-current flow of steam either prevents the air inside of the paper web from entering the steam chest 4, or sucks the air out of the sheet.

The paper entrance designated broadly as 35 consists of a slot between two L-shaped members 36 and 37 which may be adjusted relative to each other to vary the space between them. This may be done by means of knurled knobs 38. The adjustment of these two members controls, to a large extent, the aspirating effect 40 which is obtained by permitting steam to enter through the pipes 5 and 6, altho the adjustment of valves 7 and 8 likewise controls the aspirating of the paper web.

In order to prevent the steam from rushing in 45 through the pipes 5 and 6 and displacing walls 24 and 25, and in order to make the steam circulate rapidly and satisfactorily, I prefer to provide similar brackets 40 on each of the side walls 41 of the steam chamber and to provide the 50 brackets 40 with downwardly extending baffle plates 42. As will be seen by the arrows, these plates deflect steam entering through these pipes so that it will be distributed uniformly without undue pressure on any part of the steam chest.

55 While I circulate steam in the steam chest quite freely, and at a high velocity, I prefer to use it in such a way that no appreciable pressure is built up in the steam chamber and so that the steam entering the pipes 5 and 6 will pass up 60 through the aspirator and out of the paper entrance. Thus the pressure is insufficient to cause the steam to pass out through the paper exit beneath the surface of the size. I have found that steam from a 20 lb. line passing 65 into the steam chest from a $\frac{3}{4}$ inch pipe produces the desired results although this is only by way of example and does not limit my invention.

The paper exit is preferably formed by the 70 bottom walls 32 and 33 of the hinged sections, and I likewise prefer to provide two similar up-standing flanges 44 on the two sections which are spaced apart a sufficient distance to allow the paper to pass freely down between these 75 members. It will be noted that the bottom walls

of the steam chamber are substantially at, or below the level 3 of the size 2 in the tank 1 and that the paper web passes directly from the paper exit into the size without being allowed to come in contact with air. The reason for 5 this is as follows.

As the paper comes in over the guide roller 10, while it may have been partially or entirely dried by the drying rolls 11, nevertheless, considerable air and/or moisture will remain between the fibers of the sheet. This prevents successful sizing. As the paper passes down through the paper entrance formed by the walls 36 and 37, the steam is passing out from this paper entrance, as indicated in Fig. 1, and carries 15 out with it all the air which was included between the fibers of the sheet coming from the drying rolls 11.

This takes place very rapidly. It is possible to 20 operate my sizing machine with the paper moving at relatively high speeds, such as 120 feet per minute. In fact my improved method of sizing permits machines to be run at any commercial speeds. Thus, the actual time of the steam treatment is exceedingly brief because I 25 have found that a steam treatment tank, approximately twelve inches long, will be entirely satisfactory. If the paper web should be traveling 120 ft. per minute it would therefore be steam treated in about a half of a second. Of course, these figures are given by way of illustration only, and the size of the steam chest may be varied to suit the particular conditions under which the paper is made. The necessary step 30 is to treat the entire sheet with a blast of steam. 35

As the paper passes down between the Venturi plates 24 and 25, the air is entirely removed from the interior of the paper web. In fact, I believe the blast of steam prevents any air being carried 40 into the steam chest 4. The web is then passed directly beneath the surface 3 of the size 2. The size is, of course, cooler than the steam, and, any steam in the sheet will be condensed, but one part in fourteen hundred of water resulting from such 45 condensation is immaterial. No air is permitted to contact with the paper web after it passes into the steam chest and before it enters the sizing solution. Atmospheric pressure or the pressure on the sizing solution immediately forces the size 50 thoroughly into and through the sheet and completely sizes the paper. In fact, I have found that I can place so much sizing in a paper sheet that the resulting paper is unsatisfactory. This, however, can be very easily prevented by controlling the amount of steam through the valves 7 55 and 8, and/or controlling the width of the paper entrance lips 36 and 37. The less the sizing which is required, the less steam which needs to be admitted to the steam chest 4. The sizing, of course, can also be controlled by the viscosity of 60 the sizing bath.

One of the features of my present invention is that my method permits the use of a sizing bath of high viscosity and at the same time provides a 65 means for causing such a sizing bath to penetrate into the paper. Such a size may be a 6 per cent solution. A 2 per cent solution may be considered a normal one. Since air has been entirely removed from the paper web, the sizing bath is forced into the sheet, even though it is considerably more viscous than the bath normally used.

In Fig. 4 I have shown a modified form of adjusting mechanism for the lips 36 and 37 of the paper entrance plates. As indicated in Figs. 4 and 5, the rails 50 and 51 are provided with open- 75

ings 52 and 53 in which cams 54 and 55 rest, these cams being movable about the shafts 56 and 57 by means of the knurled heads 58 and 59. In this modification of my invention, both rails 5 are made adjustable to and from each other, whereas in the form shown in Fig. 3, only one rail is made adjustable to and from the other, which may be fixedly mounted.

It is immaterial just how this adjustment is 10 made, the adjustment being primarily necessary in initially securing the proper amount of steaming of the sheet. For instance, it is possible to cause more or less aspirating effect on the sheet by regulating the width of the paper entrance to 15 the steam chamber. It is also possible to vary the effect of the steaming by altering the amount of steam through an adjustment of the valves 7 and 8, and the viscosity of the size can also be used to control the amount of sizing.

20 The method of treating a wet or dry strip of paper by means of a short contact with rapidly moving steam and passing it directly through a sizing bath without permitting air to come in contact with the sheet has produced an improved 25 product, and while it may not be clear as to exactly what occurs in this steam treatment—that is, as to whether the air in the sheet is not permitted to enter the steam chamber at all or whether the air is sucked or drawn out by the 30 steam as it passes in a countercurrent flow over the sheet, it is not important and I do not wish to confine myself to any particular theory of operation of my method and machine for sizing paper.

It is, however, quite clear that a very short 35 steam treatment of the paper web before plunging it into the sizing solution enables the web to take up a much greater proportion of size than heretofore, and enables the sizing solution to be much more viscous than the normal sizing 40 solutions. In addition, by steaming the paper, as above described, the machine may be run at a relatively high speed without in any way impairing the sizing operation. I have found paper made in known machines can be increased 45 in strength about fifty per cent (Mullen test) the sole difference in the two papers being the use of my improved method of sizing, and I have found that the fold test (Schopper test) indicates a strength increase of approximately ten 50 times. The figures vary somewhat with the stock used, but illustrate the results which can be obtained by utilizing my improved method and apparatus for sizing.

Moreover, I have found that paper which has 55 been insufficiently sized can be re-sized by re-running through a steam sizing machine, and the strength of the paper can be greatly increased by the additional size which can be placed in the web. Thus my method may be carried out as a separate operation entirely successfully with previously sized or unsized paper,

although it is more economical to carry out my method as a step in a complete paper making machine.

While I have shown in somewhat simplified form and on an exaggerated scale a preferred embodiment of a machine constructed in accordance with my invention, it is obvious that a great many variations can be made from the structure shown and described, and I contemplate as included in the scope of my invention 10 all such forms of machines, and methods as may come within the terms of the appended claims.

Having thus described my invention, what I claim as new and desire to be secured by Letters Patent of the United States is:

1. The method of sizing paper which comprises treating paper with high velocity steam, excluding air from the paper, and plunging it into a sizing bath.

2. The method of sizing paper continuously 20 which comprises treating a moving paper web with a countercurrent flow of steam immediately preceding its introduction into the sizing bath.

3. The method of sizing a continuously moving 25 paper web which comprises passing the paper web through high velocity steam passing in an opposite direction to that in which the paper passes and immediately submerging the paper in size.

4. The method of sizing a continuously and rapidly moving paper web which comprises treating the paper web with a short treatment of high velocity steam and passing the web immediately into a sizing bath.

5. The method of sizing a continuously moving paper web that consists in treating a small area of the web very briefly with a steam blast and plunging the steamed paper directly into the sizing bath.

6. The method of sizing paper which consists in blowing a blast of steam across the entire sheet just before said sheet is plunged into a sizing bath.

7. The method of sizing paper which comprises subjecting a continuously moving paper web to the action of flowing steam, replacing the air in the sheet with steam and causing the steam-filled sheet to pass beneath the surface of a sizing bath, condensing the steam in the 50 sizing bath and impregnating the sheet with size.

8. The method of sizing a long paper strip which comprises moving the strip continuously through flowing live steam to carry away air in the sheet, replacing the air with steam and causing the 55 steam-filled sheet to pass immediately into a relatively cool sizing bath, condensing the steam in the sheet beneath the surface of the sizing bath, and causing the size to replace the steam in the paper.

GEROULD T. LANE.
